BRUSH MAT OR THE LIKE

William A. Lombardi, Derby, Conn.

Application September 22, 1950, Serial No. 186,210

22 Claims. (Cl. 15—171)

My invention relates to brushes and in particular to supporting means for brushes composed of one or more strip-type brush elements. The invention is in the nature of an improvement over constructions shown in my co-pending patent applications Serial No. 750,928, filed May 28, 1947, now Patent No. 2,651,798, granted September 15, 1953; Serial No. 141,420, filed January 31, 1950, now Patent No. 2,736,916, granted March 6, 1956; and Serial No. 165,929, now Patent No. 2,753,586, granted July 10, 1956, filed June 3, 1950.

It is an object of my invention to provide an improved construction of the character indicated.

It is another object to provide improved clamping means for a brush-supporting structure of the character indicated.

It is a further object to provide an improved support means for a brush strip.

It is also an object to provide a single unitary brush-strip supporting means which may integrally include all the means necessary for permanently clamping the brush strip to the supporting means.

It is a specific object to provide a brush-mat assembly comprising essentially only a plurality of spaced brush strips and simple retainers for said strips, without requiring the mounting of said retainers upon a special base.

It is a general object to provide such a simple and cheap brush-supporting structure that it will not be economically feasible to reuse the structure once the brush elements become worn, so that the supporting structure may be assembled to brush elements so permanently as never to permit the loss or dislocation of a brush element.

Other objects and various further features of novelty and invention will be pointed out or will occur to those skilled in the art from a reading of the following specification in conjunction with the accompanying drawings. In said drawings, which show, for illustrative purposes only, preferred forms of the invention:

Fig. 1 is a fragmentary view in perspective of an assembled brush mat incorporating features of the invention;

Fig. 2 is a view of brush-supporting means used in the assembly of Fig. 1, shown prior to assembly of the brush strips thereon;

Fig. 3 is a side view of the brush-supporting means of Fig. 2 with brush strips inserted therein and prior to a clamping operation;

Fig. 4 is a view similar to Fig. 3 but with the parts shown after a clamping operation;

Fig. 5 is a view similar to Fig. 2 but showing a modified construction;

Fig. 6 is a fragmentary view in perspective of a further modified brush-supporting means of the invention;

Fig. 7 is a fragmentary view in perspective of a still further modified brush-supporting means of the invention;

Fig. 8 is a perspective view of the supporting means of Fig. 7, shown in a flexed condition during an assembly of a brush mat;

Fig. 9 is a fragmentary perspective view of an assembled brush mat utilizing supporting means of Fig. 7; and

Fig. 10 is another fragmentary perspective view showing a modified version of the arrangement of Fig. 9.

Briefly stated, my invention contemplates the use of a basically simple, single supporting means to provide the sole anchorage for a plurality of brush strips, as in assembling a brush mat. By use of my improved supporting means there need be no further assembly of the brush-supporting means to a base or other mounting means, for the supporting means itself may securely hold the strips in assembled relation, whatever the asymmetry of stress on the assembly during use.

To accomplish such rigid support each supporting means may be a channel member with generally vertically projecting lugs providing for each brush strip at least two spaced points of anchorage to the supporting means. In one general form to be described, slotted brush-strip-receiving openings are defined between upstanding lugs which may be pierced out of the base of the supporting means or which may be cut out of upstanding walls of the channel member; in this form, the vertical projection of the slot area, at least in the vicinity of the slot mouths, is greater than the effective cross-sectional area of brush-strip binders to be accommodated therein, so that the brush strips may be slidably inserted in the supporting member for anchorage, as by a downward deformation of the lugs between slots. In another general form, the slotted openings, at least at the mouths thereof, are more constricted than the corresponding cross-sectional area of the brush-strip binders, so that deformation of the holder is necessary to open the slots for reception of brush binders; in this latter form, the brush-supporting means may be brought back to its original shape, through inherent resiliency of the supporting means or by securing means, in order that the brush strips may be crimped by the relatively constricted slots in which they are received.

Referring to Figs. 1 to 4 of the drawings, my invention is shown in application to a brush mat composed of a plurality of longitudinally spaced generally transversely extending brush strips 11. Each strip 11 may comprise bristles 12 wrapped around a core 13 and held in place by means of a binder member 14, which may be crimped as shown in Fig. 3 to hold the bristles around the core and the core in the binder.

According to a feature of the invention, a plurality of generally similar longitudinally extending brush-supporting means or holders 15—16 may suffice to hold a rigid mat assembly. Each of the holders 15—16 may be of generally channel-shaped form, and the side walls of channels may be utilized in the support and retention of the brush-strips. I have shown one form of assembly for the end-supporting members 15 and another form for central support, but it will be appreciated that the principles of each may be the same.

In the form shown, the basic channel member may be formed from a single piece of sheet material and comprises a base portion 17 which may be flat and longitudinally extensive. Side walls may be bent up from the opposite longitudinally extending sides of the base 17, and a plurality of slots 18 may be punched out of one side wall to correspond with another plurality of brush-retaining slots 19 punched out of the other side wall. The spaces between slots may then define retaining lugs 20—21 for holding the brush strips. As in the case of forms described in my above-mentioned co-pending application, the vertical projection of the slot openings 18—19 may exceed the effective cross-sectional area of the brush binder 14 to be received therein so that free sliding insertion is permitted. However, at the mouths of the slots 18—19, the side portions converge, as at 22, to a spacing exceeding the maximum width of the bulbous base of the brush binder 14 but still in clearance relation with the crimped upper portion thereof. Thus,

when assembling a plurality of brush strips 11 to a plurality of supporting members 15-16, the end view may appear as in Fig. 3, with a brush binder 14 loosely accommodated in all slots. To complete the assembly, the lugs 20-21 need only be deformed, as by downwardly bending the same until the constricting projections 22 bind against or crimp the bulbous lower part of the binder 14.

When all lugs 20-21 of a particular brush holder have thus been crimped against a plurality of brush strips 11, it will be appreciated that each brush strip is supported rigidly at transversely spaced points, thus positively preventing any twisting (in the horizontal plane) of the brush strips with respect to the brush holder. Use of a plurality of such holders 15-16 may provide mutual reinforcement of this strong anchorage so that a complete assembly need rely upon no further means to improve rigidity.

For appearance' sake, and also to improve retention of the brush strip 11 during assembly, each of the end brush holders 15 may further include an upwardly extending flange 23 of a continuous nature and in line with a horizontal projection of the slots 18-19. In the form shown, the flange 23 forms one leg of an angle member, the other leg 24 of which is secured, as by spot welds 25, to the base 17 of the brush holder.

In certain applications, as when the brush mat is to serve for tee-off purposes for golfers, it is desirable that the brush strips 11 be placed relatively closely together with the adjacent bristles of adjacent brush strips 11 mingling at the outer fringes, as shown at 12' in Fig. 3. Also, it is desirable that the mat shall include means for anchoring the same to the ground to prevent dislodgment in the event of abuse. Anchoring means may be conveniently carried by the brush-holder members 15-16, and in Fig. 2 I show a simple lug 26 pierced out of the base 17 of the holder for this purpose. The lug 26 is preferably bent along an axis 27 generally transversely of the golf-driving direction so as to offer maximum resistance to dislodgment; generally, it is preferred that the brush strips 11 shall be aligned with the driving direction and, therefore, the bend axis 27 is preferably generally longitudinally extending, as shown.

As indicated generally above, the retaining lugs may, if desired, be pierced out of the base of one of the holder members, and in Fig. 5 I show such an arrangement for the case of an end holder 28. The holder 28 may again be of channel shape, with a base 29 and two upwardly projecting longitudinally extending side walls 30-31. As before, retaining slots 32 may be provided in one of the side walls (31) so that the side wall 31 may comprise essentially a longitudinally extending plurality of deformable lugs 33. The other side wall (30) may be longitudinally continuous and serve as the end-retention side wall, corresponding to member 23 in the arrangement of Fig. 2. The second longitudinally extending plurality of retaining lugs 34 may be pierced or drifted out of the body of the base 29, so as to project upwardly and to present the same general appearance in the vertical projection as do the lugs 33 on the side wall 31. Assembly of a construction as shown in Fig. 5 with a plurality of brush strips 11 may be the same as that already described for the arrangement of Fig. 2, with the lugs 33-34 merely being deformed in order to crimp the brush strips 11 firmly in place, so that each brush strip may be anchored to the brush holder at two transversely spaced points of support.

In the arrangements thus far discussed, it will be appreciated that the bottoms of the slot openings may be in the sam general plane as the upper surface of the base of a particular brush holder. The base may then provide extensive bottoming support for the brush binders. However, in an attempted economizing of material such lowered slots may weaken the brush holder so as to make it unduly flexible longitudinally. To offset this

difficulty, which may arise from a use of relatively thin-gauge material, I show in Fig. 6 a suitably reinforced arrangement, again made from a single piece of sheet material.

5 In the brush holder of Fig. 6, the assembly is again channel-shaped, with a base portion 35 and upwardly extending side walls. The bottom of the slotted openings 36 in the side walls may still be in the general plane of the upper surface of the base 35, but the bottoms of slots 10 36 are spaced from the bottoms of the side walls by an amount sufficient to produce the desired reinforcing effect. Thus, the side walls may include a continuous, un-slotted part 37 projecting downwardly from the base 35, and another continuous part 38 projecting upwardly to 15 join the base 35. If desired, the downwardly projecting part of the side walls and the upwardly projecting portion 38 may be intermediately adjacent and crimped against each other for mutual reinforcement. Assembly of the 20 holder of Fig. 6 to brush strips 11 may be effected in the same lug-deforming manner as has been described.

In the forms thus far discussed, slotted openings have been initially formed with a greater effective cross-sectional area than the brush-strip-binder portion to be received therein, and the lugs have been deformed in order 25 effectively to reduce this cross-sectional area to produce the crimping action. In the other general arrangement of the invention, the slotted openings in the channel side walls are initially formed with greater constriction than the corresponding part of the brush-strip binder, so that 30 a deformation of the holder itself is necessary before the brush binder may be accommodated at all; the brush binders are then secured in place upon a substantial restoration of the holder to its original shape, thus crimping the brush binders at the location of the relatively constricted slot openings.

One arrangement of the second general form of the invention is shown in Figs. 7, 8, and 9. Initially, the holder 40 may generally resemble one of the holders (16) of the first-described arrangement, but, as indicated, the slot openings 41-42 in the opposite side walls are more constricted, at least at the convergent-mouth portions 43, than are the corresponding parts of the brush-strip binders 14; in order 45 effectively to enlarge the constricted openings, the brush holder 40 itself must be deformed. Such deformation may involve a deliberate twisting of a plurality of the brush-retaining lugs 44, as disclosed in the above-mentioned patent application Serial No. 165,929, the twisting serving to open-up the constrictions in the slots so that after insertion of brush strips a twisting of lugs 44 back into their original shape may serve to crimp the brush holders in place. However, in the form shown all the slots may be opened up by a longitudinal flexing or arching of the brush holder 40, as illustrated in Fig. 8. Once arched, as by employment of a suitable jig, all brush strips may be freely inserted, and upon release from the jig the inherent resiliency in the material of the brush holder may seek to restore the same to its original shape with the lugs 44 crimped against the brush strip 11. In certain cases, as when the material of the brush holder 40 does not have the inherent resiliency to produce the desired crimping action, suitable securing means may be provided in the base 46 of the holder, as in the case of the securing hole 47 shown. In the event of 60 employment of securing means, it may be preferable to mount the entire assembly upon a base or mounting member 48, and I have shown mounting screws 49 to pass through holes 47 to hold spaced parts of each holder member 40 to the base member 48.

In Fig. 10, I show still further modification of brush-holding means of the invention. Again, the holder employs a channel comprising a base 50 with integral side walls 51-52, but the side walls 51-52 are bent downwardly. Slotted openings 53-54 are again formed in the side walls and these openings face upwardly, but

base 50 is slotted at 55 between corresponding slots 53—54 in the side walls.

If the holder of Fig. 10 is to be used without initial deformation to accommodate slidable insertion of the brush strips 11, then the vertical projection of slot openings should allow sufficient clearance for such insertion; however, the mouths of the slots preferably converge in the particular manner discussed in connection with Fig. 2, so that the width of slots 55 in the base 50 may be less than the maximum width of the bulbous lower part of the brush binders 14. The brushes may then be secured in place by a downward deformation of the central part of every other (or of each) span 56 between adjacent slots 55 in the base 50, as will be clear. If it is desired to enhance the securing action upon such deformation, mounting screws or other holding means may be inserted through holes 57 in the base 50 for anchoring an assembly to a mount of the kind shown at 48 in Fig. 9.

In an alternative employment of a structure as described in Fig. 10, the initially formed area of the slotted openings 53—54 may be more restricted, at least in the convergent mouths thereof, than is the corresponding part of the brush binders 14 to be accommodated. The slots may then be opened upon a longitudinal flexing deformation of the kind described in connection with Fig. 8 and, after the brush strips 11 have been inserted, the structure may be allowed resiliently to return towards its original shape, thus crimping all brush binders in place. Again, if desired to improve the security of the assembly, mounting screws or the like may be driven through securing openings 57 in the base 50, as will be clear.

It will be seen that I have described an ingenious brush-supporting means which may materially simplify processes of making brush-mat assemblies. My supporting means alone, when crimped against a plurality of brush strips, may be sufficient in itself to provide a completely rigid assembly so that no further mounting of the assembly to a board or the like is necessary.

While I have described my invention in detail for the preferred forms shown, it will be understood that modifications may be made within the scope of the invention as defined in the appended claims.

I claim:

1. As an article of manufacture, a brush mat comprising a plurality of transversely spaced longitudinally extending channel members, each channel member including a base and two spaced upwardly extending walls, corresponding substantially upwardly extending parts of each of said walls having a plurality of upwardly open slots therein thereby defining upstanding retaining lugs between adjacent slots on each wall, and a single generally transversely extending brush strip with a binder received in slots of both said walls in each of a plurality of said channel members, each of said slots conforming to the contour of said binder and converging at the mouth thereof to an extent to partially overlap and thus to retain said binder.

2. An article according to claim 1, in which there is a plurality of longitudinally spaced transversely extending brush strips with binders received in slots of both said walls of both channel members, in which the corresponding ends of adjacent brush strips are in general longitudinal alignment, and in which the channel member near said end includes an end-retaining flange extending upwardly around said corresponding ends of said strips and in general longitudinal alignment with said ends.

3. An article according to claim 1, in which downwardly projecting anchoring means is integrally formed with the base of one of said channel members.

4. An article according to claim 3, in which said anchoring means comprises a lug pierced out of said base and bent along a generally longitudinally extending fold.

5. As an article of manufacture, a brush-strip holder comprising a channel member with a base and two spaced substantially parallel walls, extending substantially perpendicular to said base, substantially parallel parts of each of said walls having a plurality of upwardly open slots therein, thereby defining retaining lugs between adjacent slots in each wall, slot spacings on one wall corresponding with slot spacings on the other of said walls, whereby a single brush-strip binder inserted in corresponding slots of both walls may be anchored to both walls and thus may be retained against twisting dislocation with respect to said channel, said channel member including at one side thereof a flanged side member spaced outwardly from the body of said channel and with an upwardly extending continuous wall covering at least part of transverse vertical projections of said slots.
6. A brush holder of sheet material including a generally flat longitudinally extending base with a continuous longitudinally extending side wall bent integrally from one side of said base, and a longitudinally extending plurality of brush-strip-retaining lugs struck up directly from and out of the body of said base and spaced from said wall, whereby said base may extend both transverse sides of said lugs for more stable support of a brush-strip inserted between adjacent lugs.

7. A brush-strip holder comprising an elongated channel with a base and downwardly extending side walls on opposite sides of said base, said side walls having formed therein upwardly open slots having converging side walls at the upper open mouths thereof, said base being slotted continuously between corresponding slots in said side walls, whereby brush-strip binders may be inserted in corresponding slots of both side walls and in the corresponding slot of said base.
8. A holder according to claim 7, and securing means on said base for anchoring the same to a mounting member.

9. A holder according to claim 7, in which the vertical projection of said slot openings is more restricted than the effective cross-section of a brush-strip binder to be received therein.

10. As an article of manufacture, a brush mat, comprising a plurality of transversely spaced longitudinally extending channel members, each channel member including a base and two upwardly extending walls, each of said walls having a plurality of upwardly facing laterally open slots therein, thereby defining retaining lugs between adjacent slots on each wall, a plurality of longitudinally spaced generally transversely extending brush strips with binders received in slots of both said walls of both said channel members, the vertical projection of corresponding slots in both said walls of one member in the direction of alignment of said corresponding slots being more restricted than the effective cross-sectional area of a brush strip binder to be accommodated in said corresponding slots, so that said channel members must be arched to accommodate said brush-strip binders, a mounting member to accommodate said channel members, and means for securing upwardly arched portions of said channel bases to said mounting member.

11. As an article of manufacture, a brush mat, comprising a plurality of transversely spaced longitudinally extending channel members, each channel member including a base and two upwardly extending walls, each of said walls having a plurality of upwardly facing laterally open slots therein, thereby defining retaining lugs between adjacent slots on each wall, a plurality of longitudinally spaced generally transversely extending brush strips with binders received in slots of both said walls of each of said channel members, the vertical projection of corresponding slots in both said walls of one member in the direction of alignment of said corresponding slots having an area in excess of the cross-sectional area of a brush binder, and the mouths of said slots being more restricted than the maximum width of a brush.

binder, so that each brush binder may be slidingly inserted through a plurality of corresponding slots in each channel member and then anchored by downward bending of adjacent lugs.

12. As an article of manufacture, a brush-strip holder comprising a channel member with a base and two spaced substantially parallel walls extending substantially perpendicular to said base, substantially parallel parts of each of said walls having a plurality of upwardly open slots therein, thereby defining retaining lugs between adjacent slots in each wall, said slots having mouths converging to partially close off the slot openings, slot spacings on one wall corresponding with slot spacings on the other wall, whereby a single brush-strip binder inserted in corresponding slots of both walls may be anchored to both walls and thus may be retained against twisting dislocation with respect to said channel, the base of said channel member including a portion in general alignment with bottoms of corresponding slots in both said walls, whereby said portion may provide reinforced relatively extensive bottoming support for a brush-strip binder secured to said holder.

13. As an article of manufacture, a brush-strip holder comprising a channel member with a base and two spaced substantially parallel walls extending substantially perpendicular to said base, substantially parallel parts of each of said walls having a plurality of upwardly open slots therein, thereby defining retaining lugs between adjacent slots in each wall, said slots having mouths converging to partially close off the slot openings, slot spacings on one wall corresponding with slot spacings on the other wall, whereby a single brush-strip binder inserted in corresponding slots of both walls may be anchored to both walls and thus may be retained against twisting dislocation with respect to said channel, the bottoms of said slots being in the general plane of the base of said channel member and said channel member being of flexible material, the mouths of said slots converging towards each other so as to provide greater constriction at the mouths of the slots than is the corresponding width of a brush-strip binder to be accommodated in said slots, whereby upon flexing said channel member said slots may be effectively opened up to accommodate insertion of brush-strip binders, and securing means on the base of said channel member, whereby said base may be secured to a mounting member of less curvature than the curvature necessary to open said slots for insertion of the brush-strip binder so that upon securing the base of said channel said slots will be forcibly constricted to crimp brush binders securely in place.

14. As an article of manufacture, a brush-strip holder comprising a channel member with a base and two spaced substantially parallel walls extending substantially perpendicular to said base, substantially parallel parts of each of said walls having a plurality of upwardly open slots therein, thereby defining retaining lugs between adjacent slots in each wall, said slots having mouths converging to partially close off the slot openings, slot spacings on one wall corresponding with slot spacings on the other wall, whereby a single brush-strip binder inserted in corresponding slots of both walls may be anchored to both walls and thus may be retained against twisting dislocation with respect to said channel, the bottoms of said slots being in the general plane of the base of said channel member and said channel member being of flexible material, the mouths of said slots converging towards each other so as to provide greater constriction at the mouths of the slots than is the corresponding width of a brush-strip binder to be accommodated in said slots, whereby upon flexing said channel member, said slots may be effectively opened up to accommodate insertion of brush-strip binders, so that upon releasing said channel member after insertion of brush-strip binders the inherent resiliency of said channel member will effectively close said slots to anchor said binders.

15. As an article of manufacture, a brush-strip holder comprising a channel member with a base and two spaced substantially parallel walls extending substantially perpendicular to said base, substantially parallel parts of each of said walls having a plurality of upwardly open slots therein, thereby defining retaining lugs between adjacent slots in each wall, said slots having mouths converging to partially close off the slot openings, slot spacings on one wall corresponding with slot spacings on the other wall, whereby a single brush-strip binder inserted in corresponding slots of both walls may be anchored to both walls and thus may be retained against twisting dislocation with respect to said channel, the bottoms of said slots being spaced upwardly from the bottoms of said side walls, whereby the unslotted lower parts of said side walls may offer reinforcement against longitudinal bending of said channel member, said base being elevated from the bottom of said side walls and in general alignment with the bottoms of said slots, whereby said base may provide longitudinally extensive bottoming support for brush-strip binders held in corresponding slots of both said side walls.

16. As an article of manufacture, a brush-strip holder comprising a channel member including an elongated base with integral elongated spaced walls on opposite sides thereof and including portions extending generally perpendicular to said base, a perpendicular portion of one of said walls having a plurality of upwardly open slots therein, thereby defining retaining lugs between adjacent slots on said one wall so that a plurality of longitudinally spaced generally transversely extending brush strips may be received in said slots with the ends of said brush strips in limiting abutment with the other of said walls, a longitudinally extending plurality of further retaining lugs being pierced out of the base of said channel in general conformity with the spacing and size of the lugs defined by the slots in said one wall, whereby said channel may provide two transversely spaced anchoring points for each brush strip and at the same time provide a limiting means for corresponding ends of the brush strip.

17. As an article of manufacture, a brush mat, comprising a generally flat horizontal base member, a plurality of transversely spaced longitudinally extending channel members mounted on the upper surface of said base member, each channel member including two transversely spaced upstanding side walls, each of said walls having a plurality of upwardly facing laterally open slots therein, thereby defining retaining lugs between adjacent slots on each wall, base means integrally connecting each lug of one wall with the corresponding lugs of the other wall, a plurality of longitudinally spaced generally transversely extending brush-strips with binders received in slots of both said walls of each of said channel members, the vertical projection of corresponding slots in both said walls of one member in the direction of alignment of said corresponding slots having an area in excess of the inserted cross-sectional area of a brush binder, and the mouths of said slots being more restricted than the maximum width of a brush binder, so that each brush binder may be slidably inserted through a plurality of corresponding slots in said channel members, and means securing said base means to said base member.

18. An article according to claim 17, in which said base means integrally connects the lower parts of said corresponding lugs.

19. An article according to claim 17, in which said base means integrally connects the upper parts of said corresponding lugs.

20. An article according to claim 17, in which the bottoms of said slots are spaced upwardly from the bottoms of said side walls, whereby the unslotted lower parts of said side walls may offer reinforcement against longitudinal bending of said channel member.

21. As an article of manufacture, a brush-strip holder comprising a channel member with two elongated substan-

tially parallel vertical walls in transversely spaced relation, each of said walls having along the length thereof a corresponding plurality of upwardly open slots therein, thereby defining retaining members between adjacent slots in each wall, substantially flat connecting means in a plane generally perpendicular to those of said walls and integrally connecting and transversely spacing said walls with respect to each other, said slots having mouths converging to partially close off the slot openings, whereby a single brush-strip binder inserted in corresponding slots of both walls may be anchored to both walls at transversely spaced locations and may thus be retained against twisting dislocation with respect to said channel.

22. As an article of manufacture, a brush mat comprising a plurality of transversely spaced longitudinally extending channel members, each channel member having two elongated substantially parallel vertical walls in transversely spaced relation, each of said walls having along the length thereof a corresponding plurality of upwardly open slots therein, thereby defining retaining members between adjacent slots in each wall, substantially flat connecting means in a plane generally perpendicular to those of said walls and integrally connecting and transversely spacing said walls with respect to each other, and a single generally transversely extending brush strip with

10
5 a binder received in slots of both said walls in each of a plurality of said channel members, each of said slots conforming to the contour of said binder and converging at the mouth thereof to an extent to partially overlap and thus to retain said binder.
